UNITED STATES PATENT OFFICE.

PETER BALLAŽ, OF WEST NEW YORK, NEW JERSEY.

THREADLESS BOLT.

Application filed March 14, 1923. Serial No. 624,972.

To all whom it may concern:

Be it known that I, PETER BALLAŽ, a citizen of Czechoslovakia, residing at West New York, in the county of Hudson and State of New Jersey, have invented certain new and useful Improvements in Threadless Bolts, of which the following is a specification.

This invention relates to a means for holding any desired parts together, and it has for an object to provide a novel and improved device of this kind which may be readily applied and which obviates the disadvantage of tendency to loosen such as is common in nut and bolt locking devices.

For further comprehension of the invention, and of the objects and advantages thereof, reference will be had to the following description and accompanying drawings, and to the appended claims in which the various novel features of the invention are more particularly set forth.

Fig. 1 of the drawings is a perspective view showing my improved device in use holding two plates together.

Fig. 2 is an enlarged perspective view of the device removed.

Figs. 3 and 4 are detail perspective views respectively of the releasing and adjusting tools.

Fig. 5 is a fragmentary longitudinal sectional view this view being taken along the line 5—5 of Fig. 6.

Fig. 6. is a transverse sectional view taken on the line 6—6 of Fig. 5.

Fig. 7 is a similar view to Fig. 5 but showing the adjusting tools in position on the bolt.

As here embodied my improved device comprises a bolt 10 of circular cross section and having an integral head 11 at one end adapted to engage one of the elements to be secured together, and which carries a series of spring latches 12 near its other end which are adapted to engage the other of the said elements. These latches 12 are here shown as pivoted as at 12' to the separate end element 14, and being urged outwardly by flat springs such as 15, outward movement being limited by tips 12" on the latches engaging

shoulders 10" on the bolt. This end part is formed with an axial socket 16 which fits freely over a diminished pin-like projection 17 from the main body of the bolt. Extending forwardly from the main body of the bolt 10, in longitudinal registry with the pin 17, is a cylindrical member 18 which is suit-

ably slotted from its forward end rearwardly to receive the latches 12.

Extending from the part 14 toward the main body of the bolt is a sleeve-like projection or extension 19 which fits freely over the pin 17 and is formed with a series of longitudinally spaced and circumferentially extending notches 20 adapted to be engaged by the inturned forward ends of a series of levers 21 pivoted between their ends in the extension 18 as indicated at 22, whereby the part 14 is locked to the main body of the bolt. The said ends of the levers 21 are held in engagement with the notches by means of springs such as 23 bearing outwardly on their other ends. Formed in the extension are apertures such as 24 which register with the last mentioned ends of the levers.

In the use of my improved device, as will be apparent, the parts, such as the plates 25, to be held together will be provided with apertures of a size to snugly receive the bolt 10, and when the latter is being inserted in the said apertures the latches 12 will be swung inward by engagement with the walls of the apertures, springing out behind the said parts to hold them together.

To remove the bolt I provide the implements shown in Figs. 3 and 4, that shown in Fig. 3 comprising a sleeve 30 which is placed over the part shown in Fig. 4 and forces the latches 12 inward, the part 14 being of less diameter than the main body of the bolt so as to keep the sleeve within the confines of the latter and permit of its extending into the apertures in the parts being unlocked. The sleeve 30 may have a pair of handles such as 31 thereon, and may carry a hook 32 for a purpose to be presently set forth.

If it is desired to vary the distance between the latches 12 and the head 11 I make use of the sleeve 30 in conjunction with the implement shown in Fig. 4 and which comprises a shank 35 having on one end a series of outwardly flaring spring fingers 36 having inturned ends 37. This implement is placed on the end of the device with the fingers 36 extending between the latches 12, the sleeve 30 being first slipped on the shank 35 as indicated in dotted lines. The finger ends 37 are brought into registry with the apertures 24 in the extension 18, and when the sleeve 30 is moved over the fingers 36 these ends are projected inward through said apertures and bear on the levers 21 as in-

dicated in Fig. 7 and disengage the latter from the notches 20 in the sleeve extension 19, thereby freeing the part 14, which can be moved longitudinally to such new position 5 as may be desired, the latches 12 being readily grasped by hand for such longitudinal adjustment. The shank 35 may have formed on the end thereof opposite that from which the fingers 35 project, the head 10 39 on which is secured a handle 40, while it may be also provided with an eye 32' to receive the hook 32 and thereby retain the sleeve in position on the shank. When the device is being unlocked the fingers 36 may 15 be placed over the latches 12, and when the sleeve 30 is moved forward the ends 37 of the fingers will move the latches inward.

While I have illustrated and described a preferred embodiment of my invention, it is 20 to be understood, that I do not limit myself to the precise construction herein shown, and that various changes and modifications might be made therein without departing from the spirit and scope of the invention 25 as defined in the appended claims.

Having thus described my invention, what I claim as new and desire to protect by Letters Patent of the United States is as follows:

30 1. A device of the class described comprising a bolt consisting of a main body having a head at one end, a longitudinally adjustable part on the other end of said main

body, radially adjustable latches carried by 35 said part, a hinged locking element carried by said main body within the confines thereof, said part presenting a series of longitudinally spaced elements adapted to be releasably engaged by said locking element to hold the said part locked to the said main 40 body.

2. A device of the class described comprising a bolt consisting of a main body having a head at one end, a longitudinally adjustable part on the other end of said main 45 body, and spring latches carried by said part, a number of levers carried by said main body within the confines thereof, said part having longitudinally spaced notches engaged by said levers to hold the said part 50 locked to the main body.

3. A device of the class described comprising a bolt consisting of a main body having a head at one end, a longitudinally adjustable part on the other end of said main 55 body, and spring latches carried by said part, a number of levers carried by said main body within the confines thereof, said part having longitudinally spaced notches engaged by said levers to hold the said part 60 locked to the main body, and springs bearing on said levers to hold them in engagement with the said notches.

In testimony whereof I have affixed my signature.

PETER BALLAŽ.
